UNITED STATES PATENT OFFICE.

JOSEPH W. BALET, OF NEW YORK, N. Y., ASSIGNOR OF ONE-HALF TO
ROBERT DUNLAP AND LUKE F. COZANS, OF SAME PLACE.

DYNAMO-ELECTRIC MACHINE.

SPECIFICATION forming part of Letters Patent No. 899,646, dated March 19, 1889.

Application filed February 1, 1888. Serial No. 262,634. (No model.)

To all whom it may concern:

Be it known that I, JOSEPH WILHELMUS BALET, a subject of the King of the Netherlands, at present residing in the city, county, 5 and State of New York, have invented a new and Improved Dymano-Electric Machine, of which the following is a specification, reference being had to the annexed drawings, forming a part thereof, in which—

10 Figure 1 is a partial longitudinal section of the field-magnet and a transverse section of the armature, taken on the line A B of Figs. 3 and 4. Fig. 2 is a partial side elevation. Fig. 3 is a partial vertical transverse section 15 taken on the line C D in Fig. 2; and Fig. 4 is a partial transverse section of the field-magnet and a longitudinal section of the armature, taken on the line E F in Fig. 1.

Similar letters of reference indicate corresponding parts in all the views.

The object of my invention is to build a dynamo-electric machine in which the fluctuations of the current induced in the armature will not react upon the field-magnet, so as to 25 modify the lines of force and cause the current to fluctuate.

My object is, further, to produce an armature in which thorough ventilation is secured, thereby preventing the armature from becoming warm.

My invention consists in a dynamo-electric machine having an armature-core grooved longitudinally with respect to the armature and transversely with respect to the field-magnet, and in the combination therewith of 35 one or more conductors wound in the grooves of the armature.

It also further consists in a ventilating device, whereby the temperature of the armature is kept down by a forced circulation of air, all as hereinafter more fully described.

The field-magnet A, which is of the usual form, is provided with pole-pieces B B', which are connected by non-magnetic frames C C', 45 attached to the sides of the pole-pieces of the field-magnet. The lower polar extremity, B', of the field-magnet is formed integrally with the base D, the said base being provided with a standard, E, for supporting 50 the journal-box F of the armature-shaft G. One end of the armature-shaft G is journaled

in the box F, and the opposite end is journaled in a journal-box, H, supported by arms a, connected with the frame C'. The field-magnets are wound in the usual way, and 55 may be placed in the circuit in accordance with the requirements of the case.

The hub g' on the armature-shaft is threaded to receive the collars I I', which are provided with the concave shoulders b for receiving the ends and inner portions of the armature-ring J. The core K of the armature-ring is preferably laminated and formed in several sections, l', and intervening air-spaces c. The armature-core thus formed of 60 laminæ and provided with the air-spaces is furnished with series of longitudinal grooves d, extending from the periphery of the armature toward the center thereof radially, and in the bottom of each groove is placed a conductor, e. The conductor is wound in the grooves over the ends of the ring and within the ring in the usual way, and each section of the conductor thus arranged is connected with the bar f of the commutator-cylinder L. 65

The commutator-cylinder L is mounted upon the shaft G with the several parts insulated from the shaft and from each other in the usual way. The core of the armature-ring J is mounted upon arms g, connected 70 with the hub g' on the armature-shaft G, said arms being received in grooves in the hub g' and in the inner surface of the armature-core. The collars I I' are apertured and provided with oblique wings or vanes h, which 75 are adapted to gather the air and force it into the interior of the armature to be carried outward by centrifugal force through the air-spaces c. The commutator-cylinder L is touched by brushes M, held by studs N, received in the arm O, but prevented from electrical contact with the said arm by insulating-disks j. The arm O is arranged to turn inwardly upon a sleeve formed of the extensions of the journal-box F. The longitudinal 80 grooves d can be cut in parallel with the axis of the armature-core, or they can be cut in so as to form a spiral line on the armature, or one-half can be cut in so as to form a left-handed spiral line and the other half so as to 85 form a right-handed spiral line, thus enabling the grooves d to contribute to a thorough ven-

tilation of the armature. It will be understood that the grooves *d* can also be applied in the drum-armature.

By arranging the conductors of my armature within the periphery of the armature-core in the manner described I am enabled to cut the lines of force by the armature-core and to induce in the armature very strong magnetism, which acts inductively upon the conductor of the armature, producing a current which is taken off from the commutator by the commutator-brushes in the well-known way. By placing my conductor so far within the periphery of the armature-core, I am enabled to avoid the reactionary effect upon the field-magnet produced by fluctuations in the current in the circuit of the dynamo, and by separating the conductors by the radial projections of the armature, I am enabled to prevent self-induction in the conductor. The radial slots in which the conductor is received also act to force the magnetic lines of force to flow without any leakage through the conductor and the armature-core. The oblique wings or vanes *h* on the collars I gather a sufficient quantity of air to keep down the temperature of both the conductor and the armature-core. By means of these several improvements I attain a high efficiency without any disadvantages in the construction of the machine.

Having thus described my invention, I claim

as new and desire to secure by Letters Patent—

1. In a dynamo-electric machine, an armature-core provided with longitudinal grooves extending inward from the periphery thereof to a depth much greater than the diameter of the conductor, and a conductor arranged at the bottom of the grooves and in close proximity to the walls of the grooves, substantially as specified. 35

2. In a dynamo-electric machine, the combination, with the hollow armature-core, of collars arranged to partly support the armature-core and provided with apertures and inclined wings *h* for introducing air into the interior of the armature, substantially as specified. 40

3. In a dynamo-electric machine, the combination, with the field-magnets *A*, provided with polar extremities *B*, adapted to inclose the sides of the armature, of the armature having the laminated longitudinally-grooved core *K*, the grooves extending inward from the periphery of the core to a depth much greater than the diameter of the conductor, the conductor in the bottom of the said grooves, and the commutator and electrical connections, substantially as described. 50

JOSEPH W. BALET.
